POST CAP AND TRUSS TIE UNIT

George E. France, 901 W. James St.,
Geneva, Ill. 60134

Continuation-in-part of abandoned design application Ser. No. 249,760, May 2, 1972. This application July 10, 1974, Ser. No. 487,129

Term of patent 14 years

Int. Cl. D25—01

U.S. Cl. D25—61

FIG. 1 is a side elevation of a post cap and truss tie unit having a portion broken away and omitted for convenience of illustration and associated with a fragmentary post and truss assembly, the latter being represented in broken line.

FIG. 2 is a section taken at 2—2 in FIG. 1.

FIG. 3 is a perspective view of the left end of the post cap and truss tie unit embodied in my new design shown in FIG. 1 and FIG. 2.

FIG. 4 is a bottom view of the showing in FIG. 3.

The broken line showings of the post and truss in FIGS. 1 and 2 are for illustration purposes only.

This application is a continuation-in-part of my copending application Ser. No. 249,760, filed May 2, 1972, now abandoned, and entitled Truss Post Cap.

I claim:

The ornamental design for a post cap and truss tie unit, as shown and described.
